WALTER PIERNAY, OF STETTIN, GERMANY, ASSIGNOR TO STETTINER CHAMOTTE-FABRIK ACTIEN-GESELLSCHAFT VORMALS DIDIER, OF STETTIN, GERMANY.

FURNACE FOR BURNING REFUSE.

1,211,875.

Specification of Letters Patent.

Patented Jan. 9, 1917.

Application filed May 16, 1914. Serial No. 839,129.

To all whom it may concern:

Be it known that I, WALTER PIERNAY, engineer, citizen of Germany, residing at No. 25 Saunierstrasse, in the city of Stettin, 5 German Empire, have invented new and useful Improvements in Furnaces for Burning Refuse; and I do hereby declare the following to be a full, clear, and exact description of the same.

10 The invention relates to improvements in furnaces for the combustion of refuse and the like having no grate. In furnaces of this kind the material to be burnt is fed in, during the operation of the furnace, from 15 above, in the same degree in which the combustion takes place, and the slag and ashes are removed at the bottom of the shaft. The removal of the slag is effected by moving a cutting device through the furnace shaft, 20 whereupon the sole closing the shaft at the bottom is pulled out. The loosened end of the slag column can then fall downward. Thereafter the furnace sole is again inserted and pressed tight, and the slag removing 25 device, which in the meantime has carried the charge, is pulled back.

My invention has the object, in the first place, to so construct and arrange the means for cutting out the slag column and for 30 moving the sole of the furnace, that the attendance can take place from the front of the furnace, so that the workmen are not forced to remain in the pit into which the loosened slag falls. For the purpose of 35 cutting through the slag a portable device is used, according to my invention, which is moved on rails to the furnace cell from which the slag must be removed. This carriage has a sliding cutting device and means 40 for pulling out, and again putting in, the sole of the furnace. In order to cause the slag to adhere to the furnace shaft as little as possible and to enable it to move downward as easily as possible, it is preferable to 45 provide the combustion shaft with a water-cooled iron mantle. This iron mantle has at its lower end tubular openings in which double conical nozzles are exchangeably inserted. Through these nozzles the air necessary for the combustion is blown in and 50 one feature of my invention consists in the fact that the distance of the narrowest sec-

tion of the nozzle from the interior mantle of the combustion shaft is about one third of the thickness of the cooling mantle, so 55 that the currents cross each other behind the narrowest section of the nozzle at a point which is still within the nozzle, thus outside of the combustion shaft. Further essential features of my invention will be 60 referred to in explaining the drawings, in which one construction of the invention is shown by way of example.

Figure 1 is a vertical section through a furnace cell of a furnace for burning refuse. 65 Fig. 2 is a front elevation of a furnace on a larger scale. Fig. 3 shows the means for fastening the slag removing carriage to the furnace. Fig. 4 is a section through the lower part of the cooling mantle on a larger 70 scale. Fig. 5 shows a section on the line A—B of Fig. 4. Fig. 6 is a longitudinal section through a nozzle on a larger scale. Fig. 7 represents the slag removing carriage in section on the line C—D of Fig. 8. Fig. 75 8 is a front elevation of the slag removing carriage and Fig. 9, a plan of same. Fig. 10 shows the removable furnace sole in vertical section. Fig. 11 is a section on the line E—F of Fig. 10. Fig. 12 is a section 80 of another construction of the furnace sole. Fig. 13 represents the releasable coupling between the slag removing carriage and the sole of the furnace.

The shaft of the furnace consists of the 85 filling chamber 1, the combustion chamber 2 and the slag chamber 3, which is closed at the bottom by the removable sole M. Essential for the operation of the furnace is the slag removing carriage N, on which 90 the slag cutting device O is arranged. In order to prevent the slag from adhering to the wall of the combustion chamber, this chamber 2 is surrounded by a cooling mantle 4. The cooling water is fed through the 95 pipe 5 at the bottom end of the mantle and can issue again at the upper end of the mantle through the pipe 6 in a hot condition. Near to the lower end of the cooling mantle double conical nozzles are inserted in 100 the tubes 7, through which nozzles the air required for the combustion, the so-called blast, enters. The air is fed through the pipe 9 and passes through the funnel shaped

branch pipe 9' into the annular chamber 10, into which the nozzles 8 enter. The interior section of a tube 7 corresponds to the outer diameter of the double conical nozzle 8, which is preferably so formed that the narrowest section, as shown in Fig. 6, is at a distance from the interior of the mantle equal to about one third of the thickness of the cooling mantle 4. In this construction of the nozzle the crossing point 12 of the air currents have accordingly time to unite again before they impinge on the charge. By this means the air can penetrate to the middle of the refuse column 15 without eddying currents being formed. Experiments have shown that by using the new nozzles the consumption of power in blowing in the air is much reduced, while on the other hand the output of the furnace 20 is considerably increased.

The slag removing carriage N has wheels 14 keyed on the shaft 13 and running on the rails 15, can therefore be moved from one furnace cell to the other. That is effected by turning the hand crank 16, on the shaft 17 of which a chain wheel 18 is mounted, from which a chain 19 passes to the chain wheel 20 keyed on the shaft 13.

When the slag removing carriage N has been moved into the correct position before the furnace cell from which the slag is to be removed and the opening 21 in the wall of the furnace has been made clear, the slag cutting device O is moved toward the furnace. This cutting device has a frame 22 consisting of U-iron or the like and wheels 23 which run on the rails 25 fastened to the frame 24 of the slag removing carriage N. The slag cutting device proper 40 consists preferably of a frame 27 covered by the plate 26, on the front wall of which the knife 28 of cast steel is removably attached by screws 29. This knife, in the preferred form, has a wedge shape in cross section, (Fig. 7) and has a curved front cutting edge 30 (Fig. 9). When the slag cutting device O is moved toward the furnace cell on the rails 25, the front part of the U-iron frame 22 enters the opening 21. In order to fasten the slag cutting device in this position bolts 31, pivoted to the wall of the furnace 32, are thrown over ears 33 fastened to the U-iron 22 (Fig. 3). The cutting movement can be given to the knife 28 by any suitable mechanism, for example, by spur-wheel gearing turned by hand, or by an electromotor or other engine. In the example illustrated a hydraulic press is shown for the purpose, the frame 27 of the slag cutting device being fastened to the piston rods 34 of two hydraulic cylinders 35 fastened to the frame of the slag removing device O. The parts required for operating the hydraulic cylinder are not

shown, because they can have any desired construction and do not form a part of the present invention. If water is forced into the cylinder 35 the piston rods 34 move the frame 27 and the knife 28 fastened thereto through the furnace. The slag cutting device is guided by the rails 36, which are embedded in the brickwork of the furnace. On these guide rails run the wheels 37 carried by the frame of the slag cutting device. Because the cutting surface of the knife 28 is inclined at an acute angle to the guide rails 36, no pressure is exerted backward in cutting the slag column, but the charge over the cutting plane is rather raised and glides over the slag cutting surface of the knife onto the platform 26. The part of the slag underneath the cutting plane rests on the platform 38 of the movable furnace sole M and must fall when this sole is pulled out.

The platform 38 is fastened on the frame 39 of U-iron or the like, in which the shaft 40 is journaled. On this shaft 40 are secured the worms 41, each of which engages in a worm wheel on one of the two shafts 43. Each shaft 43 rotates in bearings 44 secured to the frame 39. Outside of the bearing 44 the supporting wheels 45 are adapted to rotate on the shafts 43 and run on the rails 46. On the extreme end of the shafts 43 the eccentrics 47 are keyed, which rest on the rails 48. Not only the rails 46, but also the rails 48 are fastened on brackets 49 which are secured in the brickwork of the furnace. As will be evident, on turning the shaft 40 through the agency of the worm gearing 41, 42, the shafts 43, and consequently also the eccentrics 47, are uniformly turned. When the shaft 43 turns in one direction, the frame 39 is raised together with the platform 38 and thus the platform is pressed against the knife edges 50 provided on the lower edge of the furnace shaft, while by turning in the opposite direction the platform 110 is lowered and the sole of the furnace thus released. The same result is obtained in the construction shown in Fig. 12 in a simpler manner by the middle axes of the supporting wheels 45, which rotate on the reduced pins 43' of the shafts 43, being displaced for a few millimeters in regard to the middle axes of the shafts 43. By turning the shafts 43 the frame 39 and foundation plate 38 are raised or lowered. The rotation of the shaft 40 takes place by means of a hand crank, which is placed on the square provided on the front end of the shaft.

As soon as the sole of the furnace is lowered, thus loosened, it can be moved on the rails 46. This motion takes place from the slag removing carriage N, and for this pur-

pose the arm 52 provided on the sole of the furnace is coupled with the sliding toothed rack 53 of the slag removing carriage. The front end 54 of the arm has for this purpose a fork shape and the corresponding end 55 of the toothed rack 53 has an eye. The end 55 can be introduced into the fork 54 and by inserting a pin 56 through the opening 57 of the end 55 and through the opening 58 of the fork 54 the arm 52 may be connected with the toothed rack 53. Of course the connection between the arm 52 and toothed rack 53 may be effected in any other suitable manner. Further instead of the toothed rack any other known gear may be used, by means of which from the slag removing carriage N the furnace sole M can be moved backward and forward. The toothed rack 53 runs on rolls 59 adapted to turn in standards 60. These standards 60 are secured to the frame of the slag removing carriage N. In the toothed rack 53 engages a spur-wheel 61, on the shaft 62 of which the larger spur-wheel 63 is keyed which engages with the spur-wheel 64 on the pins 65 of the handle 66. By the rotation of this handle the toothed rack 53 is moved backward and forward.

If the slag is not removed the opening 21 through which the slag cutting device O is inserted, is closed by a slide 67 while the opening 68 by which the sole of the furnace is removed, is closed by a slide 69. Both slides 67 and 69 are connected by rods 70 and carried by cords 71 hanging from rolls 72 on the shaft 73. On this shaft 73 are also secured rolls 74 on which by means of ropes 75 the counter weights 76 are supported. The counter weights 76 are of such dimensions that they nearly correspond to the weight of the slides 67, 69, so that in order to move the rods only but little power is necessary. The slide 67 runs with its outside edges in guides 77 and the slide 69 with its outside edges in guides 78, while the rods 79 carrying counter weights 76 run in guides 80.

The slag removing operation takes place as follows: After the slag removing carriage N has been moved to the furnace cell from which the slag is to be removed, the workman turns on the cooling water and the air blast and by raising the slides 67 and 69 opens 21 for the slag cutting device O and 68 for pulling out the furnace sole M. Thereafter the slag cutting device O is moved toward the opening 21 of the furnace and the frame 22 is fastened by the bolt 31. By introducing water under pressure into the hydraulic cylinder 35 the slag cutting device O is moved through the shaft of the furnace, so that the part of the slag underneath the cutting edge 30 of the knife 28 is cut off. Thereafter the front furnace

workman lowers the frame 39 together with the platform 38 for a few millimeters by turning the shaft 40, connects the toothed rack 53 of the carriage N with the arm 52 of the furnace sole M, and moves the carriage by turning the handle 66 forward, in consequence of the movement given to the toothed rack 53. The loosened slag falls, and a cylinder 81 fastened at the back end of the sole M, which, when the sole M is removed, forms an extension of the shaft 3, serves as a guide for the falling slag, so that the slag arrives on the iron transport belt 82, by which it is carried to the slag breaker. The furnace sole is then again inserted and pressed tight, the slag removing device is pulled out, and the openings 21 and 68 are closed by the slides 67 and 69.

What I claim and desire to secure by Letters Patent of the United States is:

1. In a furnace for burning refuse, the combination of a shaft; a removable sole at the bottom of the shaft; a carriage in front of the shaft; a slag cutting device on said carriage and comprising a part adapted to be projected into the shaft; and a means carried on the carriage for operating the sole.

2. In a furnace for burning refuse, the combination of a shaft; a removable sole closing the bottom of said shaft; a carriage; a slag cutting device on said carriage and adapted to be moved toward said shaft; a rack on said carriage; an arm removably connecting said sole and rack; and means carried on said carriage and operatively engaging said rack.

3. In a furnace for burning refuse, the combination of a shaft; a removable sole closing the bottom of said shaft; a carriage; a slag cutting device on said carriage and adapted to be moved toward said shaft; a rack on said carriage; an arm removably connecting said sole and rack; a pinion on said carriage engaging said rack; and means carried by the carriage for operating the pinion.

4. In a furnace for burning refuse, the combination of a shaft; a removable sole closing the bottom end of said shaft; a frame carrying said sole; wheels carrying said frame; and means carried with said wheels and adapted to move the center of said wheels and thus to raise and lower said sole.

5. In a furnace for burning refuse, the combination of a shaft; a removable sole closing the bottom end of said shaft; a frame carrying said sole; wheels carrying said frame; and eccentrics adapted to move the center of said wheels and thus to raise and lower said sole.

6. In a furnace for burning refuse, the combination of a shaft; a removable sole

closing the bottom end of said shaft; a frame carrying said sole; wheels carrying said frame; and eccentrics carried by said wheels and adapted to move the center of said wheels and thus to raise and lower said sole.

In testimony whereof, I have signed my

name to this specification in the presence of
two subscribing witnesses.

WALTER PERNAY.
